NONGLARE HEADLIGHT

Horace T. Eddy, Omaha, Nebr.

Application March 16, 1933, Serial No. 661,082

3 Claims. (Cl. 240—41.35)

My invention relates to headlights, and more particularly to non-glare headlights.

It is a purpose of my invention to provide a new and improved headlight comprising new and improved means for mounting the lamp in the headlight so that there will be no direct light from the lamp shining out through the lens, but all the light will be reflected by the reflector provided for that purpose in the headlight.

It is a further purpose of my invention to provide a mounting for a headlight comprising means whereby the lamp is so mounted that the same faces the reflector, or in other words, so that the lamp socket which receives the lamp will have the lamp receiving opening thereof facing the upper portion of the reflector near the innermost portion thereof, or adjacent the axis of the reflector where said axis meets said reflector surface. The axis of the socket preferably extends at an oblique angle to the axis of the reflector so as to be inclined in a direction such that the lamp receiving opening will face a portion of the reflector slightly above the axial center thereof, and so that the axis of the reflector and the axis of the socket will make an angle of approximately 15 degrees to each other.

It is another purpose of my invention to provide a mounting for a lamp bulb in a headlight which will hold the bulb in a reverse position from that usually occupied by the bulb, or with the metal end or base thereof nearest the lens, so as to utilize the structure of bulbs which allow only a small portion of the rays of light to extend from the filament toward the base of the bulb.

It is a further purpose of my invention to provide a mounting for a lamp bulb in a headlight comprising a tubular standard having a lamp receiving opening in the upper end thereof, which is directed in a general direction toward the reflector of the headlight, and which is provided with a shield for keeping any direct rays of light from the filament of the bulb from shining out through the lens of the headlight.

It is a further purpose of my invention to provide a device of the above mentioned character having a shield that is formed by providing a widened or enlarged portion at the upper end of the standard, which is so shaped and so located as to serve as a shield, which is integral with said tubular standard and which extends upwardly therefrom at an oblique angle to prevent any upward passage of the rays of light from the filament above the upper end of the standard.

It is another purpose of my invention to pro-

vide means for adjusting the focus of a headlight of the above mentioned character by providing means for adjusting the standard in a direction parallel to the axis of the reflector.

It is another purpose of my invention to provide a shield of the above mentioned character, which is provided with a reflecting surface, this being preferably obtained by chromium plating the shield.

Other objects and advantages of my invention will appear as the description of the drawing proceeds. I desire to have it understood, however, that I do not intend to limit myself to the particular details shown and described, except as defined by the claims.

In the drawing:

Fig. 1 is a vertical sectional view through a headlight, partly broken away, showing my invention applied thereto.

Fig. 2 is a vertical sectional view through the standard utilized in connection with my invention, partly broken away.

Fig. 3 is a fragmentary face view of the shield.

Fig. 4 is a plan view of the standard mounting block.

Fig. 5 is a section taken on the line 5—5 of Fig. 2.

Fig. 6 is a fragmentary vertical sectional view through a portion of a headlight showing a modification of my invention, and

Fig. 7 is a plan view of the mounting block used in conjunction with the form of invention shown in Fig. 6.

Referring in detail to the drawing, my invention is shown as being applied to a headlight having a reflector 10, a casing portion 11 and a lens 12. A pair of openings 13 is also provided in the casing 11, which may be in the form of slots. A tubular standard 14 is provided for the support of the lamp in the headlight, and said standard 14 is provided with a base flange 15, which has a pair of threaded openings 16 therein that are adapted to receive the screw-threaded headed fastening members 17, which extend through the slots 13 and which also extend through a slot 18 in the mounting block 19.

Said mounting block 19 is provided with openings 20 for fixing the same in position on the casing 11 by means of rivets or similar fastening members, or the block may be soldered or brazed to the casing 11. The block 19 is made with its upper face parallel to the axis of the reflector 10 and with the lower face thereof conforming to the shape of the casing 11 at the point of securement thereto, the upper surface of the block 19

being thus always flat, while the lower surface thereof may be of various shapes, depending on the shape of the casing member 11 to which it is applied. The lower face of the flange 15 is also flat and it will thus be evident that the standard 14 can be moved along the top of the block 19 either backward or forward in the direction of the slot 18 to the extent permitted by said slot 18, whereby the standard 14 can be moved bodily 10 parallel to the axis of the reflector 10 so as to focus the headlight.

The standard 14 has the main portion thereof extending in a substantially vertical direction and has a rearward bend at 21 providing an upper 15 end portion 22 that is inclined at an oblique angle to the portion 14, and at an oblique angle to the axis of the reflector 10 so that the upper extremity 23 thereof faces the reflector 10, and the axis of the portion 22 would intersect the reflector 10 above its vertex. The axis of the inwardly and rearwardly inclined portion 22 of the standard 14 preferably makes an angle of approximately 15 degrees to the axis of the reflector 10.

25 The upper side of the tubular member 22 at its upper extremity 23, is provided with an ear or lip portion that is formed by spreading the end of the tube forming the standard, laterally, and shaping the same so that it will be substantially 30 flat and will extend at an oblique angle to the tubular portion 22 to provide a shield 24, which extends upwardly and inwardly at an oblique angle from the point where it joins the member 22, thus extending not only at an oblique angle 35 to the axis of the tubular portion 22, but also at an oblique angle to the axis of the reflector. The shape of the member 24 is shown more clearly in Fig. 3, and has a relatively narrow portion 25 where it joins with the tubular portion 22, but 40 is extended laterally so as to provide a relatively short shield in a vertical direction, but which is elongated considerably in a transverse direction.

It will be obvious that the shield 24 can be formed from the tubular member 22 by providing 45 a longitudinal slit in the tubular member, and a pair of transverse slits therein, whereby the tubular member can be opened up and spread out into a flat form, but the shield portion will still remain integral with the tubular portion 22. The shield 24 may be chromium plated if desired, 50 to provide a reflecting surface thereon facing the lamp bulb 26 of the usual double filament type, through which the axis of said reflector passes between said filaments.

55 The standard 14 is slotted in the tubular portion 22 thereof so as to provide a long longitudinal slot 27 therein having a lateral offset 28 therein between the ends thereof, said lateral offset 28 having an enlargement such as is commonly provided in a bayonet slot. Preferably a pair of slots 27 is provided at diametrically opposite points, and a substantially cylindrical insulating 60 plug 29 fitting within the cylindrical passage in the portion 22 of the standard 14 has a pair of 65 projections 30 that are adapted to be received in the slot 27, the slot 27 thus limiting the inward movement of the insulating plug 29. The insulating plug 29 carries a pair of contact pins 31 and 32 in longitudinal passages provided therein, which are provided with springs 33 for forcing 70 the same outwardly and which have the conductors 34 and 35 electrically connected therewith in any suitable manner, the conductors 34 and 35 being mounted in a cord or cable 36 that 75 extends lengthwise through the tubular member

14 to an opening 37, through which said cord 36 passes into the space 38 between the reflector 10 and casing 11 and from that point out of the headlight in the usual manner to suitable switching means provided for manipulating the supply 5 of current to the lamp 26 to burn the same brightly or dim the same.

The contact members 31 and 32 engage with the usual contacts 39 and 40 provided on the base portion 41 of the lamp 26, said base portion having 10 the usual projections 42, which are adapted to engage in the lateral offsets 28 of the slots 27, thus holding the contacts 39 and 40 in engagement with the contacts 31 and 32, with the springs 33 under slight compression.

15 If the wiring for the headlight is to be concealed, but is to come out through the casing instead of passing between the casing and the reflector, the arrangement shown in Fig. 6 and the adjustable block shown in Fig. 7, are adapted to 20 be used instead of the form of the invention shown in Figs. 1 to 5 inclusive. The standard 14' shown in Fig. 6, is made in the same manner as previously described, except that the tubular portion has no opening 37 therein, the conductor 25 cord 36 extending downwardly through the opening in the bottom of the member 14 and through the opening 18' in the casing 11'.

The block 19' is made in a similar manner to the block 19, being secured to the casing 11' in 30 the same manner as previously described, but instead of being provided with a slot, is provided with a relatively large central opening 44, which is elongated in the direction of the length of the block 19, and has narrow extensions 45, which 35 are slots serving the purpose of the slot 18 shown in Fig. 4. The fastening elements 17 extend through the portions 45 of the opening and the relatively large portion 44 of the opening is provided to accommodate the conductor 36 so that 40 the standard 14 can be adjusted on the block 19' in the same manner as can the standard 14 on the block 19. The block 19' is made with a plane or flat top face so as to permit sliding 45 of the flange 15 thereon, and the lower face of the block 19' is shaped to conform to the shape of the casing 11' for the purposes previously described. The opening 18' is preferably made to conform in shape substantially to that of the opening in the block 19'. 50

What I claim is:

1. In a headlight, a concave reflector, a standard having one end thereof located adjacent the axis of said reflector, a lamp socket on said end of said standard having a lamp receiving opening facing the inner portion of said reflector, the axis of said socket extending at an oblique angle to the axis of said reflector approximating 15 degrees, a base for said standard and means for slidably mounting said base for adjustment parallel to the axis of said reflector to move said socket along said axis to focus said headlight, said mounting means being so constructed as to maintain the same angular relation of the axis of said socket to the axis of said reflector for any adjusted position thereof along said axis. 55

2. In a headlight, a casing, a concave reflector, an upstanding tubular standard in said headlight having an inwardly and upwardly obliquely extending upper end portion inclined at a sharp acute angle to the axis of said reflector, contacts mounted in said end portion of said standard, conductors in said standard leading from said contacts, said standard having a lamp receiving 70 75

means fixedly mounted thereon adjacent said contacts having its axis extending at a sharp acute angle to the axis of said reflector and mounting a lamp bulb lying on said axis, and
5 means for mounting said standard on said casing for adjustment relative to said reflector parallel to the axis thereof to focus said headlight, by moving said bulb along said reflector axis, said adjusting means comprising a base fixed on
10 said standard having a plane under face extending parallel to the axis of said reflector, a guide block on said casing having a plane top face, said base being mounted for guided sliding movement on said block, and means for clamping said base to said block in any adjusted position thereof.

3. In a headlight, a casing, a concave reflector, an upstanding tubular standard in said headlight having an inwardly and upwardly extending upper end portion extending at a sharp acute angle to the axis of said reflector, contacts mounted in said end portion of said standard, conductors in said standard leading from said contacts, said standard having integral lamp receiving means provided thereon adjacent said contacts and an upwardly and inwardly inclined 10 shield integral with said standard extending from the end thereof at a sharp acute angle to the vertical, said shield being substantially flat and elongated in a transverse direction.

15
